UNITED STATES PATENT OFFICE.

ALFRED HEYDEMANN, OF FRANKFORT-ON-THE-MAIN, GERMANY.

DEVICE FOR LIFTING DOCUMENTS, &c., OFF FILES OF ANY KIND.

No. 895,268.

Specification of Letters Patent.

Patented Aug. 4, 1908.

Application filed November 19, 1907. Serial No. 402,809.

To all whom it may concern:

Be it known that I, ALFRED HEYDEMANN, a subject of the Emperor of Germany, residing at Frankfort-on-the-Main, Germany, have invented new and useful Improvements 5 in Devices for Lifting Documents, &c., Off Files of any Kind, of which the following is a specification.

My invention relates to an improved device 10 for lifting documents such as letters, bills etc. off files of any kind, the device being so constructed that the documents rest on a shovel-like blade or board, on which they are pressed by clamps of different lengths, so 15 that said documents are kept in relative position and the tubes formed by the perforations of each sheet remain unimpaired. As a consequence such documents, after selecting the one desired, can easily be replaced.

20 The device comprises two or more pairs of clamps pivoted on a common axis at the back of the shovel-like blade. Said clamps are arranged beside, and independent of each other, in such a manner that, on raising said 25 clamps, the shovel-like blade or board is not raised or brought into an inclined position. Said clamps however are so disposed with regard to each other that on raising one of the same the others are likewise raised, the 30 pressure on the documents being uniformly distributed.

In the accompanying drawing illustrating my invention the device is shown by way of example in: Figure 1 in side elevation, Fig. 35 2 in back elevation and in Fig. 3 in plan.

The shovel-like blade or board 1 rests on a doubly bent fork-shaped arm 2, at the free end of which a handle 3 is provided. On this handle is provided, behind the back 4 an 40 axis 5, which supports the clamps. The latter consist of two pairs of wires 6, 7 and 8, 9 of different lengths, which are connected together by transverse rods 10, 11, 12, 13 and 45 16 and are supported on the axis 5 by sleeves 14. The clamps are so disposed with regard to each other that one pair 8, 9 is situated inside the other pair 6, 7; by which arrangement it is assured that, in raising the inner pair, the outer pair will be lifted by the cross 50 bar 11.

To the inner pair of clamps 8, 9 is secured a handle 15 which is so arranged that it can be grasped at the same time as the handle 3.

On the handle 3 two springs 17, 18 are provided beside each other which act on the 55 cross rods 11 and 16. Owing to the arrangement, manner of supporting and different lengths of the clamps, it is assured that one short and one long arm of each pair of the clamps acts on each half of the board 1; so 60 that, in using the device, it is well balanced and all of the documents are kept in position, no matter what their size may be, while the blade or board 1 is prevented from taking an inclined position, owing to the clamps being 65 hinged to the back thereof.

The device is used as follows: The handles 3 and 15 are grasped at same time, the clamps 8 and 9 being thus raised and being caused to raise the clamps 6 and 7 by pressing 70 against the cross bar 11. The device, with the clamps so raised, is then pushed into the pile of documents and the handles 3 and 15 released. All the documents between the clamps and the bottom board are then 75 securely kept in position, so that they cannot become displaced when lifted off the file.

What I claim and desire to secure by Letters Patent is:

1. A device for lifting documents off files 80 and the like comprising in combination, a board, two clamps adapted to press on said board, a handle to open one of the said clamps and means causing this clamp to open the other clamp when opened. 85

2. The hereinbefore described device, comprising in combination, a board, an axis at the rear edge of same, a long clamp with handle on said axis, a short clamp thereon so arranged that the long clamp is located inside the short one, springs pressing said clamps on the board, and means whereby the long clamp operates to open the short clamp. 90

3. The hereinbefore described device, comprising in combination, a board, a handle attached to said board, clamps adapted to press on said board, a handle attached to one of said clamps and means to transfer the movement of this clamp to the other clamp. 95

In testimony whereof I have signed my 100 name to this specification in the presence of two subscribing witnesses.

ALFRED HEYDEMANN.
